CLAIM

The ornamental design for a blade cartridge, substantially as shown as described.

DESCRIPTION

FIG. 1 is a front isometric view of my design;

FIG. 2 is a rear isometric view of my design;

FIG. 3 is a front view of my design;

FIG. 4 is a rear view of my design;

FIG. 5 is a right side view of my design;

FIG. 6 is a left side view of my design;

FIG. 7 is a top view of my design; and,

FIG. 8 is a bottom view of my design.

The broken lines shown in the drawings are included for the purpose of illustrating an environmental structure and form no part of the claimed design.

1 Claim, 6 Drawing Sheets(56)
